WALL CONSTRUCTION

Ralph A. Bonnell, Chicago, Ill., assignor to Northwestern Terra Cotta Corporation, Chicago, Ill., a corporation of Illinois

Application October 23, 1940, Serial No. 362,328

2 Claims. (Cl. 72—16)

The present invention relates to improvements in wall construction.

More particularly the present invention relates to wall construction of the post-slab type.

In wall structures having more or less thermal communication with the earth there is considerable likelihood that unsightly and undesirable condensation will collect upon wall surfaces which may be exposed to moist and humid air and undesirable condensation may also occur upon any surfacing material applied to said exposed wall surfaces should thermal communication exist between the base wall and the surfacing material. This condition may occur in such structures as tunnels, underpasses, subways, basements and all similar sub-surface structures. Moreover, it is often desired to provide a wall facing of ceramic material, which should present a surface free from irregularities, and difficulties are frequently encountered in construction when the ceramic material is mounted upon a foundation structure which is irregular.

As immediately above suggested, one of the applications of the present invention is in subway constructions, where the wall construction at the stations is often faced with ceramic material. Such ceramic material is usually mounted upon a concrete surface in contact with the earth. The result is that under certain conditions the condensation occurs upon the facing material, producing an undesirable dampness.

An object of the present invention is to provide a wall construction which is free from this undesirable surface dampness.

A further object is to provide a wall structure which may be provided with a smooth face even though the concrete foundation thereof presents a wavy or uneven surface.

A further object is to provide an improved wall structure which is substantial and provides efficient ventilation between the facing wall and the foundation wall.

A further object is to provide a wall construction well adapted to meet the needs of commercial service.

Further objects will appear as the description proceeds.

Referring to the drawings—

Figure 1 is a transverse sectional view of a tube of a subway construction or the like at a station thereof;

Figure 2 is a sectional view taken along the plane indicated by the arrows 2—2 of Figure 1, certain facing blocks being broken away to illustrate the posts therebeneath;

Figure 3 is an enlarged sectional view taken along the plane indicated by the arrows 3—3 of Figure 2;

Figure 4 is a fragmentary view taken transversely of a subway tube or the like;

Figure 5 is a sectional view taken along the plane indicated by the arrows 5—5 of Figure 4; and

Figure 6 is an enlarged sectional view taken along the plane indicated by the arrows 6—6 of Figure 5.

The numeral 10 indicates a floor construction which may be of concrete, and the numeral 11 indicates a wall and roof construction which may also be of concrete, enclosing a space 12, which may be the station of a subway tube, the wall construction 11 being provided with the opening 13 for providing exit and discharge of passengers from the trains (not shown) in the subway tube. Said floor construction and said wall and roof construction will be referred to collectively as substructure. Said floor and wall constructions constitute a foundation member for facing blocks, to be described presently. The floor construction 10 may be covered with flooring material 14 formed to provide a gutter 15. Lining the surface of the concrete wall 11 are a plurality of facing blocks 16—16, which for the purpose of providing a proper appearance should present a smooth surface to the space 12.

Said facing blocks 16—16 are mounted upon the posts 17—17 spaced longitudinally of the subway tube, the posts being spaced so that the center lines of the posts are separated by a distance approximately equal to the length of the facing blocks 16—16. Said posts 17 are built up out of a plurality of post blocks 18—19, which should be perforated, preferably longitudinally of the subway tube, as indicated by the numerals 19—19. As indicated in Figure 3, the post blocks, which should have unglazed surfaces, are secured to the foundation wall 11 by means of mortar or the like, indicated by the numeral 20. The facing blocks 16—16, which preferably should have an unglazed rear surface, are secured to the post blocks 18—18 by means of mortar, indicated by the numeral 21. To the end that the face surfaces of the facing blocks 16—16 may be smooth and even, either the thickness of the mortar pad 20, the thickness of the mortar pad 21, or the thickness of the post blocks 18—18, or all three, may be varied to compensate for unevenness in the surface of the foundation wall 11.

55 The spaced posts 17—17 provide between them

ventilating spaces 22-22, which communicate with the space 12 adjacent to the gutter 15 through the opening 23 in the member 14. Said ventilating spaces 22-22 communicate with the space 12 adjacent to the opening 13 through openings 24. Inasmuch as the opening 23 is at a lower level than the opening 24, a circulation of air will be had through the ventilating spaces 22-22 from the opening 23 to the opening 24 due to chimney effect. Cross ventilation is had between adjacent ventilating spaces 22-22 by reason of the perforations 19-19 in the blocks 18-18.

In the construction illustrated in Figures 1, 2 and 3, it will be noted that the facing blocks 16-16 are of relatively thick construction at the regions thereof indicated by the numeral 25 located between the posts 17-17. In other words, the ends of said blocks, indicated by the numerals 26-26, are of reduced thickness where they contact with the mortar pads 21-21 of adjacent posts. This reduced thickness at the point of contact with the mortar pads 21-21 may or may not be required, depending upon the distance allowed between the face of the foundation wall and the face of the ceramic facing material. However, the portion 25 of each block 16 is sufficiently narrow so as not to provide an objectionable restriction of the passageway 22. The circulation of air in rear of the facing blocks 16-16 is therefore unobstructed, whereby condensation of moisture within the space 12 will be minimized. Any moisture which does collect within the ventilating spaces 22-22 will drain out through the openings 23 into the gutter 15.

In view of the discussion hereinabove of the structure disclosed in Figures 1, 2 and 3, it will not be necessary to proceed with an extended discussion of the structure illustrated in Figures 4, 5 and 6. As will be noted particularly from Figures 5 and 6, the facing blocks 26, which correspond to the facing blocks 16 of Figures 1, 2 and 3, are of substantially uniform thickness throughout their length, whereby to provide increased dimensions for the ventilating spaces 27, which correspond to the ventilating spaces 22 of Figures 1, 2 and 3.

The construction illustrated in Figures 1, 2 and 3 may be preferred by some by reason of the fact that it presents a more substantial wall construction while providing adequate ventilat-

ing space. Others may prefer the construction shown in Figures 4, 5 and 6, which provides a wall construction which is adequately substantial while providing greater dimensions for the ventilating spaces in rear of the facing blocks.

Both forms of the invention present the advantage that unevenness in the foundation wall structure may be compensated for by varying the thickness of the mortar pad 20, the mortar pad 21, or the post blocks 18. Both forms of the invention provide a substantial construction with adequate ventilation in rear of the facing blocks, whereby condensation will be minimized.

Though preferred embodiments of the present invention have been described in detail, many modifications will occur to those skilled in the art. It is intended to cover all such modifications that fall within the scope of the appended claims.

What is claimed is:

1. Wall construction for subearthsurface structures including, in combination, a substructure portion including a vertical wall, vertical pillars spaced along said wall, said pillars being apertured transversely parallel to said wall, said pillars being faced on their inner and outer surfaces with mortar, said pillars being secured to said substructure by the mortar on one side of said pillars, and facing blocks, said facing blocks being secured to said pillars by the mortar upon the other side of said pillars, the regions intermediate of said pillars between said substructure and said facing blocks being open to the atmosphere adjacent to their extremities, said facing blocks being spaced from said substructure to permit vertical circulation of air.

2. Wall construction for a subearthsurface enclosure having a vertical side wall and a rounded roof, said wall construction including a substructure, pillars spaced along said substructure and extending vertically along said vertical wall and across at least a portion of said rounded roof, facing blocks secured to said pillars, said facing blocks being spaced from said substructure, said pillars being apertured transversely in a direction parallel to the axis of said rounded roof, the spaces bounded by said pillars, said substructure and said facing blocks being open to the atmosphere at different levels whereby vertical circulation of air may occur through said spaces.

RALPH A. BONNELL.
